[57] CLAIM

The ornamental design for a digital audio disc player, as shown and described.

DESCRIPTION

FIG. 1 is a perspective view of a digital audio disc player showing my new design;

FIG. 2 is a top plan view of the first embodiment;

FIG. 3 is a left side elevational view thereof;

FIG. 4 is a front elevational view thereof;

FIG. 5 is a bottom plan view thereof;

FIG. 6 is a rear elevational view thereof;

FIG. 7 is a rear elevational view thereof; and,

FIG. 8 is a perspective view thereof, wherein the lid portion is in the open position. The broken line showing the insides of the digital audio disc player are for illustrative purposes only and form no part of the claimed design.

The inside portions of the digital audio disc player which are not visible in FIG. 8 form no part of the claimed design.
